BOWLING ALLEY

Ellsworth F. Seaman, Washington, D. C., and
Jesse B. Lunsford, East Falls Church, Va.Original application May 1, 1940, Serial No.
332,798. Divided and this application October
19, 1942, Serial No. 462,586

5 Claims. (Cl. 273—50)

This invention relates to bowling alleys and the pins used in conjunction with such alleys. It is a division of our application Serial Number 332,798, filed May 1, 1940.

An important object of our invention is to provide a bowling alley of improved construction in which the factors of chance and error which heretofore have entered into the games of duck pins, ten pins, and the like are largely eliminated with the result that the scores compiled by the players furnish a more reliable basis of comparison of their individual skill.

Still another object of our invention is to provide signalling means to indicate either audibly or visually, or both, when a player "lofts" or throws a ball part way down the alley, instead of rolling it down the alley as required by the rules of play. It is desirable that all players in a game compete on the same basis and subject to the same conditions. To this end the loft indicator serves to show when a player has changed his method of play to the extent that a ball is thrown instead of rolled down the alley. Furthermore, the loft signal informs the management of the bowling alley of repeated lofting on the part of a player. Since continued lofting results in damage to the floor of the alley necessitating its frequent resurfacing, the practice is to be discouraged and for this reason some alleys display the sign "Do not loft ball." By the operation of the loft signal the player is automatically reminded of his weakness and ordinarily he will strive to overcome it without placing the management to the embarrassing necessity of calling the matter to his attention.

Other objects and advantages will be apparent from the following detailed description of a preferred embodiment of our invention, reference being had to the annexed drawings, in which:

Figure 1 is a perspective view of a bowling alley including the novel features of the invention;

Figure 2 is a plan view of the forward end of the bowling alley schematically indicating the arrangement of the loft detecting means; and

Figure 3 is a wiring diagram indicating the circuits associated with the loft signalling means.

Referring to the drawings, in Figure 1 is shown a bowling alley 1 having a trough 2 extending along one of its sides and disposed at a slight inclination for the gravitational return of balls 3 from the rear end of the alley, occupied by the pins 4 (only seven pins of the usual ten being shown) to an elevated rack 5 located adjacent a runway 6 at the forward end of the alley where the players stand when rolling the balls down

the alley in playing the games of duck pins, ten pins, and the like. A narrow line 7 is customarily marked upon the floor of the alley between the alley 1 and the runway 6 which, according to the rules, no player is permitted to cross in his delivery of a ball down the alley without incurring a penalty against his score.

Preferably located along one side of the alley at the forward end within convenient view of the players is an indicator board 8. This indicator board is provided with a bank of electric lamps 9 arranged in wedge formation, each lamp corresponding to the position of a pin 4 in set-up position on the alley. The lamps of this pin diagram are individually connected to contacts embedded in the floor of the alley and designate the spotting position of the pins, so that when a pin is in set-up position a metal plate on its base bridges these contacts and closes a circuit to illuminate the lamp in the pin diagram on the indicator board corresponding to that particular pin on the alley. This indicator board facilitates keeping score and obviates error when pins left standing on the alley at the conclusion of a player's period of play are hidden behind other pins. Such a board also serves to increase the interest of spectators whose view of the alley is frequently obscured by the players. In order to protect the lamps, the diagram board may be covered by a panel 10 having glass windows over the lamps and, if desired, these windows may be numbered to designate the pin positions.

Also upon the indicator board are two additional lamps 11 and 12 designated respectively "Foul" and "Loft." The "foul" lamp 11 will light and a bell 13 connected in the same circuit will ring when a player crosses the foul line 7 marked upon the alley and the "loft" lamp 12 will illuminate and bell 13 will sound when a player lofts or throws a ball part way down the alleys.

The structure and operation of the "foul" indicating apparatus is fully described and claimed in application Ser. No. 332,798 filed May 1, 1940.

The loft detector controlling the "loft" lamp 12 comprises means for directing two beams of light, indicated by dotted lines 15 and 16 in Figure 2, horizontally across the alley short distances beyond the foul line and at an elevation above the alley such that both beams are sequentially intercepted by a ball rolling in the normal way down the alley (or, alternatively, rolling down the gutter which extends alongside the alley), but only the second light beam 16 being intercepted when the ball is lofted in such a manner as to "jump" or pass above the first light beam 15.

The first light beam 15 is directed from a light source 17 located on one side of the alley so as to impinge upon a photoelectric relay 18 located upon the opposite side of the alley. This photoelectric relay is interposed in a circuit 19 including a source of electrical energy 20 and a relay 21 as indicated in Figure 3. The second light beam 16 likewise is directed from a light source 22 at one side of the alley upon a photoelectric relay 23 at the other side of the alley interposed in a circuit 24 including a source of electrical energy 25 and a relay 26.

A hinged switch bar 27 is connected to one end of a conductor 28, which conductor at its other end taps the main line A of the building lighting system. A spring 29 tends to draw the switch bar 27 into engagement with a contact 30, but while the relay 21 is energized the switch bar is attracted and maintained out of engagement with said contact. The conductor 28 includes a solenoid 31 within which there slides a soft iron plunger 32, the arrangement being such that energization of the solenoid 31 draws the plunger to the left. A hinged switch bar 33 is connected to one end of a conductor 34 leading to a contact 35. A spring 36 tends to draw the switch bar 33 into engagement with a contact 37, but while energy is flowing through the relay 26 the switch bar is held away from said contact. The conductor 34 includes therein a solenoid 38 surrounding the plunger 32 and which when energized tends to draw the armature to the right. A contact 39 companion to contact 35 is connected by a conductor 40 to main line A. A conductor 41 extends between the pivoted switch bar 33 and a contact 42; while a contact 43, companion to contact 42, is connected to main line A by a conductor 44, and interposed in this circuit is the electrically operable signal bell 14 mounted adjacent the indicator board.

The plunger 32 has fixed thereon a bridging member 45 which, in its movement to the left with the plunger, closes the pair of contacts 35 and 39, and, in its movement in the opposite direction, closes the pair of contacts 42 and 43. A conductor 46 leading from contact 30 and a conductor 47 leading from contact 37 connect these contacts to the main line D. A conductor 48 in parallel with conductor 44 extends between the latter conductor and the winding of a solenoid operated relay 49 comprising a plunger 50 carrying a bridging member 51. The other end of the winding of relay 49 is connected to main line A through a conductor 52. One of a pair of contacts 53 on the bottom of the solenoid is connected to the main line A by a conductor 54 having interposed in circuit therewith the "loft" lamp 12; while the other contact 53 on the solenoid is joined to the main line D by a conductor 55. Normally the plunger will be depressed to maintain the bridging member out of connecting relation with the pair of contacts 53 on the solenoid, but when the solenoid is energized the plunger will move to the dotted line position of Figure 3 to connect these contacts and complete a circuit to illuminate "loft" lamp 12 on the indicator board.

From the description it will be seen that when the light beam 15 impinging on photoelectric relay 18 is intercepted, the circuit 19 is momentarily interrupted releasing relay 21 and allowing contact 30 to be engaged by the hinged switch bar 27 under the urge of spring 29. The short period of time during which the switch bar engages the contact is sufficient to cause a current

to flow from main line A, through conductor 28, including the solenoid 31, switch bar 27, contact 30 and conductor 46, to main line D. This current energizes the solenoid 31 which draws the plunger 32 to the left causing the bridging member 45 to move from its dotted line position to close the gap between contacts 35 and 39. This conditions the circuit controlled by the relay 26 so that when the second light beam 16 is intercepted by the ball, the current in circuit 24 will be momentarily interrupted, causing the relay 26 to release hinged switch bar 33 and allow the latter to be pulled by the spring 36 into engagement with contact 37. Current then flows from main line A, through conductor 40, bridging member 45, conductor 34, including the solenoid 38, switch bar 33, and through conductor 47 to main line D. The solenoid 38 moves the plunger 32 to the right to break the connection between contacts 35 and 39 and restore the armature to its original dotted line position closing contacts 42 and 43.

Now in the case of a lofted ball, only the second light beam 16 is intercepted. This causes the relay 26 in circuit 24 to be de-energized, releasing the switch bar 33 which is drawn by spring 36 into engagement with contact 37. A current is consequently caused to flow from main line A, through conductor 52, the solenoid winding of relay 49, conductor 48, conductor 44, across bridging member 45, through conductor 41, switch bar 33, and conductor 47, thence to main line D. This current operates the relay 49 to close the circuit constituted of the conductors 54 and 55 and including the "loft" lamp 12, which latter becomes lighted. The bell 14 interposed in the circuit including the conductor 44 is also sounded momentarily for the duration of the second light beam interruption.

If a player should make a loft only one of the two light beams directed across the alley will be intercepted. Interception of the second light beam 16 without interception of the first beam 15 actuates relay 49. This causes the bell 14 to sound and the lamp 12 marked "Loft" on the indicator board to illuminate in a manner which has previously been explained. The relay 49 may be reset, either manually or electrically, by means not shown but corresponding to those described in application Ser. No. 332,793 filed May 1, 1940. This extinguishes the Loft light on the indicator board. It will be readily apparent that relay 49 might be arranged to shunt out the contacts on the bowling alley and preserve the indicator board in its then fixed condition when a ball is lofted, regardless of whether or not any pins are knocked down on the roll. In this event the penalty for a lofted ball would be the same as for a foul; i. e., the player loses the number of pins he knocked down with the ball when the loft was committed. Under ordinary conditions of play, however, the sounding of the bell to indicate the occurrence of a loft will probably be sufficient.

The invention may be embodied in other specific forms without departing from the spirit or essential characteristics of the invention, and the present embodiment is therefore to be considered as illustrative and not restrictive, and all changes which come within the meaning and range of equivalency of the claims are therefore intended to be embraced therein.

What is claimed is:

1. In a bowling alley, a loft detecting device comprising, a normally closed circuit including a signaling device, a plurality of means for di-

recting light beams across the alley at spaced intervals in a position to be sequentially intercepted by a ball rolling down the alley, photoelectric means responsive to the simultaneous impingement of all of said light beams thereon for maintaining said circuit open, and means including said photoelectric means responsive to the sequential interception of said light beams for maintaining said circuit open, whereby when the light beams are not sequentially intercepted the circuit including the signaling device is normal and said device is actuated to indicate that the ball has not followed the proper path for it.

2. In a bowling alley, a loft detecting device comprising, a pair of primary circuits each including a photoelectric relay, means for directing two light beams across the alley in spaced relation so as to be normally sequentially intercepted by a ball rolling down the alley, each light beam being directed toward the light sensitive portion of the respective photoelectric relay, a secondary circuit including a signaling device, two switches in said secondary circuit, means responsive to the opening of the first of said primary circuits by interruption of the first of said light beams for opening one of the switches in said secondary circuit and means responsive to the opening of the second of said primary circuits by interruption of the second beam of light for closing the second switch in said secondary circuit, whereby, in the case of a loft, where the first beam is not intercepted by the ball and the second beam is intercepted thereby, both switches in the secondary circuit will be simultaneously closed to energize a signaling device.

3. In a bowling alley, a loft detecting device comprising, a pair of primary circuits each including a photoelectric relay, means for directing two light beams across the alley in spaced relation so as to be normally sequentially intercepted by a ball rolling down the alley, each light beam being directed toward the light sensitive portion of the respective photoelectric relay, a secondary circuit, two switches in said secondary circuit, means responsive to the opening of the first of said primary circuits by interruption of the first of said light beams for opening one of the switches in said secondary circuit, means responsive to the opening of the second of said primary circuits by interruption of the second beam of light for closing the second switch in said secondary circuit, a tertiary circuit, a signaling device in said tertiary circuit, a relay in said secondary circuit adapted upon energization to close said tertiary circuit to actuate the signaling device and means for holding said relay in tertiary circuit closing position, whereby, as in the case of a loft, when the first primary circuit is not opened and the second one is, the secondary circuit will be closed energizing the relay therein which will hold the tertiary circuit closed to give an enduring signal indicating that a loft has occurred.

4. In a bowling alley, a loft detecting device comprising, a pair of primary circuits each including a photoelectric relay, means for directing two light beams across the alley in spaced relation so as to be normally sequentially intercepted by a ball rolling down the alley, each light beam being directed to the light sensitive portion of the respective photoelectric relay, a secondary circuit including a signaling device, two switches in said secondary circuit, means responsive to the opening of the first of said primary circuits by interruption of the first of said light beams for opening one of the switches in said secondary circuit, means responsive to the opening of the second of said primary circuits by interruption of the second beam of light for closing the second switch in said secondary circuit, a tertiary circuit, another signaling device in said tertiary circuit, a relay in said secondary circuit adapted upon energization to close said tertiary circuit to actuate the signaling device therein, and means for holding said relay in tertiary circuit closing position, whereby, as in the case of a loft, when the first primary circuit is not opened and the second one is, the secondary circuit will be momentarily closed energizing the signaling device and the relay therein, the latter of which will hold the tertiary circuit closed to give an enduring signal indicating that a loft has occurred.
5. In a bowling alley, a loft detecting device comprising, a pair of primary circuits each including a photoelectric relay, means for directing two light beams across the alley in spaced relation so as to be normally sequentially intercepted by a ball rolling down the alley, each light beam being directed toward the light sensitive portion of the respective photoelectric relay and serving to maintain the respective primary circuit closed, a relay in each primary circuit, two secondary circuits each controlled and normally maintained in open position by the energized relay in the respective primary circuit, a switch located in the secondary circuit controlled by the second primary circuit, means responsive to the closing of the secondary circuit controlled by the first primary circuit for opening said switch, means including said switch responsive to the subsequent de-energization of the relay in the second primary circuit for restoring said switch to closed position in the secondary circuit, the re-energization of the relay in the second primary circuit caused by the re-establishment of the light beam after the passage of the ball immediately restoring the secondary circuit controlled thereby to open position, and a signaling device in the secondary circuit controlled by the first primary circuit, whereby a signal is given when the first light beam is not intercepted and the second is while if both are sequentially intercepted no signal will be given.
